UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

SEPARABLE CIRCUIT DEVICE.

1,139,687.

Specification of Letters Patent.

Patented May 18, 1915.

Application filed January 11, 1912. Serial No. 670,572.

To all whom it may concern:

Be it known that I, CHARLES J. KLEIN, a citizen of the United States, residing at Milwaukee, in the county of Milwaukee and State of Wisconsin, have invented new and useful Improvements in Separable Circuit Devices, of which the following is a full, clear, concise, and exact description, reference being had to the accompanying drawing, forming a part of this specification.

My invention relates to improvements in separable circuit devices.

It is particularly applicable to separable plugs and receptacles but is not limited to this particular class of circuit devices.

It is one of the objects of my invention to provide combined circuit making and holding clips which will firmly hold together the parts of a circuit device but which will at the same time permit the parts to be readily separated.

Various other objects and advantages of my invention will be hereinafter set forth.

For the purpose of clearly and fully disclosing the nature and advantages of my invention I shall describe the embodiment thereof illustrated in the accompanying drawing. My invention, however, is not limited to the specific embodiment thereof chosen for the purpose of illustration.

In the accompanying drawing, Figure 1 is a sectional view through a separable plug and receptacle with the parts separated. Fig. 2 is a perspective view of one set of circuit making and holding clips, and Fig. 3 is an elevation of the pair of clips shown in Fig. 2.

The device illustrated includes a member 1 adapted to be inserted in a lamp socket or the like and a member 2 adapted to be plugged into the member 1.

The member 1 comprises an insulating body provided with contact receiving recesses 3 and 4. Within the recess 4 which is preferably rectangular in cross section, is a contact 5 retained in place by means of a screw 6 passing through the body of the member 1 and threading into a nut 7 within the contact 5. The screw 6 may be conveniently employed as a retaining means for the usual screw shell 8, surrounding a cylindrical portion 9 of the member 1. The screw 6 when so used also serves to electrically connect the screw shell 8 to the contact 5.

The recess 3 is adapted to receive a similar

contact 10 having a lateral extension 11 which may be formed integrally therewith or separate therefrom and secured thereto in any preferred manner. The contact 10 is retained in place by means of a screw 12 passing longitudinally through the center of the member 1 and threading into the extension 11. The screw 12 also retains in place the usual center terminal 14 for the member 1 and electrically connects the same to the contact 10.

In addition to the retaining screw 6 the screw shell 8 is provided with a retaining screw 15 threaded into a nut 16 set into a recess in the member 1 preferably in alignment with the contact 10. An insulating packing 17 is interposed between the contact 10 and the nut 16 to insulate the same from one another.

The plug member 2 comprises the ordinary form of insulating body and carries contacts 18 and 19 adapted to plug onto the contacts 10 and 5 respectively of the member 1. The contacts 18 and 19 are of similar construction and each is provided with an extension 20 and binding screw 21 for connecting the same in circuit. The contacts 18 and 19 are held in place in the usual manner by screws 22.

In practice I prefer to construct the contacts as illustrated in Figs 2 and 3. As illustrated in these figures, the contacts of the member 1 comprise a resilient strip 23 of conducting material bent to bring its extremities 24 and 25 into parallel relation, the extremities being spaced as desired. Each of the contacts is thus provided with two parallel spring fingers. In one finger is provided an aperture 26 to receive a rounded projection on the cooperating contact of the plug member. Further, the fingers of each contact are provided at their extremities with inwardly inclined portions 27 offset so as not to interfere and prevent compression of the fingers as hereinafter described.

The contacts of the plug member are identical in all respects. Each comprises two rigid parallel fingers 29 and 30 spaced just a slightly greater distance apart than the fingers 24 and 25 of the contacts of the member 1. In practice I prefer to form one of these fingers integrally with the extension 20 and rivet the other finger to said extension. The fingers 29 and 30 are preferably made in the shape illustrated, being provided with

rounded portions and having their outer edges curved inwardly as shown at 31. Further, the tip of one of the fingers is provided with a conical projection 32 adapted to enter the aperture 26 in its coöperating contact finger. In practice I prefer to provide the opening and conical projection on relatively opposite fingers of the two sets of contacts.

With the arrangement described when the member 2 is plugged into the member 1 the rigid contact fingers of the former engage and compress the resilient fingers of their coöperating contacts contained in the member 1. This is facilitated by the inwardly inclined extensions 27 on the resilient contact fingers which guide the resilient fingers between the rigid fingers. The compression of the resilient fingers between the rigid fingers insures good electrical contact and causes the recessed resilient fingers to snap on to the conical projections of the rigid finger when the contacts have been telescoped to the necessary extent. This interfitting of the contact fingers and the friction caused by the compression of the spring fingers firmly holds the removal plug member 2 in place. In addition to the function described, the conically shaped projections on the rigid fingers perform another function. When the two sets of contacts are being fitted together the points of the projections naturally seek the center of the openings in the coöperating contacts. Hence these conical projections tend to align the two sets of contacts. It is accordingly unnecessary to restrict the openings in the member 1 to insure proper alinement of the contacts when the plug is inserted. In practice, for a purpose which will be shortly described, I prefer to have the openings in the member 1 considerably larger than is necessary to admit the contacts of the member 2.

Due to the peculiar construction of the contacts and the freedom of movement of the contacts of the member 2 in the openings of the member 1, the member 2 may be readily detached from the member 1 either by a straight pull or by leverage. The curvatures 31 in the outer edges of the fingers of the plug member and the lateral play of said fingers in the openings of the member 1 permit the plug member to be readily pried off by a sidewise movement, while the resiliency of the fingers of the member 1 allows the plug member to be pried off by a movement at right angles to the movement just mentioned. As a matter of fact the connection

between the two members is so resilient and pliable that the member 2 may be readily pried off of the member 1 at practically any point about the axis of the two members.

What I claim as new and desire to secure by Letters Patent is:—

1. In combination, a multipart circuit device, one part having a rigid contact and the other having a resilient contact to coöperate therewith, one of said contacts having a substantially conical projection and the other having a recess to receive said projection for alining said contacts when brought together and for releasably locking said parts against separation.

2. A multipart circuit device, one part having a longitudinally disposed recess therein, a pair of resilient contact fingers mounted in said recess, one of said fingers having an opening and the other part having a pair of longitudinally projecting rigid contact fingers, one of said rigid fingers having a conical projection thereon, said rigid contact fingers fitting over said resilient contact fingers and compressing the same and said conical projection entering said opening in one of said resilient fingers to hold the parts together, said recess being larger than said contact fingers whereby separation of the parts is permitted either by an axial pull or by leverage.

3. A multi-part circuit device, one part having parallel spring fingers adapted to yield laterally and the other having rigid parallel fingers adapted to slide over said spring fingers, coöperating fingers being provided with a yielding lock comprising a projection on one adapted to enter a recess in the other, said projection tending by its engagement with the recessed portion of its coöperating finger to aline all of said fingers.

4. A two part circuit device, one part being provided with a pair of parallel yielding contacts having inturned portions at their extremities offset with respect to each other and the other part being provided with a pair of parallel rigid contacts adapted to be plugged onto said yielding contacts and compress the same.

In witness whereof, I have hereunto subscribed my name in the presence of two witnesses.

CHARLES J. KLEIN.
